UNITED STATES PATENT OFFICE.

DNA LIVIGNANO, OF CLEVELAND, OHIO.

ARCH-SUPPORT.

No. 856,712.

Specification of Letters Patent.

Patented June 11, 1907.

Application filed August 20, 1906. Serial No. 331,235.

To all whom it may concern:

Be it known that I, DNA LIVIGNANO, a citizen of the United States, residing at Cleveland, in the county of Cuyahoga and State of Ohio, have invented a certain new and useful Improvement in Arch-Supports, of which the following is a full, clear, and exact description, reference being had to the accompanying drawings.

10 My invention relates to shoes and has for its object to provide for the same a simple, inexpensive, comfortable but efficient brace or support for the arch of the foot of the wearer.

15 As is well known, it frequently happens that one or more of the ligaments extending rearwardly from the toes become weakened or stretched, causing the arch of the foot to break down. It has been proposed to cure this by providing metallic arch-supports, which may be placed in shoes, but these are generally so constructed as to retain moisture in the covering thereof, which moisture tends to soften the ligaments and thus aggravate 25 the very fault the supports should correct. All such supports are heavy, expensive and are more or less uncomfortable to the wearer.

It is the further object of this invention to avoid these defects in supports as heretofore 30 constructed and to provide a support that may be easily applied to or built into shoes as ordinarily constructed as a part thereof. I accomplish these results by the construction illustrated in the drawings forming a 35 part hereof, wherein

Figure 1 represents a perspective view of a shoe having my invention applied thereto. Fig. 2 is a transverse sectional view through the instep portion of said shoe, and Fig. 3 is a 40 side elevation of the support detached from the shoe.

In the drawings, 1 represents the shoe proper, the same comprising the upper 2, sole 3, and welt 4. 5 denotes the instep 45 shank, and 6 the insole. On the inner side of the instep there is secured my arch support 7. The lower edge of this support is secured adjacent to the sole, being preferably inserted between the upper and the insole and 50 secured in place by any convenient means, as by sewing. The upper edge of the support 7 is inclined upwardly from front to rear to conform to the inclination of the upper at this point and is provided at its upper edge

with a reinforcing strip 8 and with eyelets 9 55 extending through said strip and the body of the support. These eyelets are spaced apart a distance equal to the distance between the eyelets 10 in the upper of the shoe, the rearmost eyelet 9 coinciding in position with the rearmost eyelet proper 10 in the upper. To provide sufficient supporting surface for the arch and to afford comfort to the wearer, the front and rear edges of the support 7 are curved, and the rear edge projects considerably beyond the top and bottom edges providing a rearward extension intermediate of the top and bottom of the support.

As will appear from Fig. 2, the support 7 is 70 of less height than the corresponding portion of the upper, whereby the action of lacing the shoe will cause the support to be drawn up into engagement with the arch of the foot and form a support therefor, even should the upper be full enough to cause the lacing to draw the opposite edges 11 thereof together. Moreover, the support 7, being of comparatively short length, will readily conform to the arch of the foot, forming an effective support 75 therefor. The support being of leather, will absorb any moisture, which will be quickly dried, owing to the exposure of the outer surface thereof to air which will be caused to circulate in the space 12 between such surface 80 and the inner surface of the upper by the movement of the shoe and foot in walking, thus enabling it to effect a cure of the defect in the wearer's foot. At the same time, the pliability and adaptability of the material of 85 which the support is made insures comfort to the wearer.

In addition to its use for supporting broken down or weak arches of the foot, my arch support is of value in shoes for children 95 learning to walk or for those having weak ankles as it enables the foot to maintain a proper position.

Having thus described my invention, I claim:

1. In a shoe, the combination of the sole and upper, of an arch support composed of pliable material having the lower portion thereof suitably secured to the shoe adjacent the sole and having its upper portion provided with lacing holes, said holes being spaced apart a distance corresponding to the distance between the lacing holes in the up- 100 105

per, the depth of said support being less than the depth of the corresponding portion of the upper, substantially as specified.

2. In a shoe, the combination of the sole and upper, of an arch support of pliable material having its lower portion suitably secured adjacent the instep portion of the sole and having its upper edge inclined to correspond to the inclination of the upper edge of the upper, said support being provided adjacent its upper edge with lacing holes spaced equidistant with the lacing holes in the upper, said support being of less depth than the adjacent portion of the upper.
- 15 3. In a shoe, the combination of the sole and upper, of an arch support of pliable material having its lower portion suitably secured adjacent the sole and its upper portion provided with lacing holes corresponding in position to the lacing holes in the corresponding portion of the upper, said support having
- 20

the body portion thereof extended beyond the top and bottom portions thereof, substantially as specified.

4. An arch support for shoes comprising a body of leather or similar pliable material adapted for application to the instep portion of a shoe and having a bottom portion adapted to be suitably secured to a shoe and an upper edge portion inclined to correspond to the inclination of the upper edge of the lacing portion of the upper and provided with lacing holes, the front and rear edges of the support being curved and the rear edge projecting rearwardly beyond the top and bottom edges thereof, substantially as specified.

In testimony whereof I affix my signature in the presence of two witnesses.

DNA LIVIGNANO.
